ELECTRIC OUTLET BOX

Ferdinand Mueller, New York, N. Y.

Application October 20, 1938, Serial No. 235,939

1 Claim. (Cl. 173—330)

This invention relates to types of electrical devices in general use and known commercially as electric outlet boxes.

An object of the invention is to provide an outlet box composed of two sections, respectively inner and outer, the latter having openings in which fuse carrying plugs may be removably engaged.

Other objects of this invention, will be apparent in the following detailed description.

An illustrative embodiment of the invention is shown in the accompanying drawing, in which:

Figure 1 is a top plan view of an embodiment of the invention.

Figure 2 is a plan view of the wall receptacle with the cover plate omitted.

Figure 3 is a top plan view of lower portion of the device as assembled.

Figure 4 is a transverse sectional view taken on line 4—4 of Figure 1 showing the contact elements.

Figure 5 is a longitudinal sectional view taken on line 5—5 of Figure 3.

Figure 6 is a front elevational view of the removable contact plug.

Figure 7 is a plan view of the contact plug.

Figure 8 is a cross sectional view taken on line 8—8 of Figure 6.

Figures 9 and 10 are plan views, showing the two equal sections of the plug with fuses assembled therewith.

Figure 11 is a plan view of a modified form of a plug.

Figures 12 and 13 are plan views of a plug showing a modified method of entering wires.

Referring to the drawing in greater detail, the numeral 15 indicates a flat plate having a beveled, down turned margin and a pair of spaced openings 16 receptive of raised elements extending outwardly from the face of an outer block 17, held by a retaining screw 18.

The front section 17 of the box has opposed inreaching recesses 19 for conductors, and a pair of spaced openings 20 to receive connection plugs.

The front of the inner block 21 has an opening 20 in register with the plate openings 20. Chambers 22 extend inwardly partially through the inner block 21 forming spaced cavities receptive of contact springs 23, and spaced recesses 24, formed at right angles to the spring chambers 22, on the opposite side of the block 21 to freely

enclose curved flat springs 25 to provide additional force to the contact springs 23.

The contact springs 23 are secured in the block 21 by screws 27, and held from contact with the conductor bars 26 except when forced outwardly by the connection plugs.

The conductor bars 26 are held securely against the outer walls of the chambers, and the units 17 and 21 are secured together by screws 28.

The connection plugs 29, which are an essential part of this invention, comprise two duplicate elements, as in Figures 9 and 10, which when placed face to face form a rectangle adapted to freely enter the openings 20 of the blocks. It will be clearly seen that as a plug 29 enters the block opening, the contact plates 33 cause the contact springs 23 to be forced outwardly against the plates 26, whereby current will be conducted through the fuse and the connection plugs.

Figures 9 and 10 show the flat inside faces of the plug elements in which are conductor channels 30, and fuse channels 31; recesses 32 form seats upon which contact plates 33 are secured, the two plug elements being firmly held together by a screw 34.

Figures 12 and 13 show a modification of the plug construction, and may be preferred when separate conductors are employed, instead of the usual twin wire conductors.

Having thus described the invention what is claimed as new and desired to secure by Letters Patent is:

In an electric outlet box, a wall receptacle comprising a pair of elongated rectangular blocks of substantially equal size and made of non-conductive material secured in juxtaposed inner and outer relation and recessed midway the length of their opposite longer side edges, flat terminals fixed in the bottoms of the side recesses of the inner block, a cover extending over the face of the outer block, said cover having openings through which portions of the faces of said outer block extend, spaced sockets in said blocks receptive of conductor plugs, curled flat spring conductors fixed on the juxtaposed face of the inner block normally extending partially into said sockets to contact an entered plug, and transversely disposed bow springs held between said blocks to reinforce said spring conductors, said conductors contacting said terminals upon the entrance of plugs in said sockets.

FERDINAND MUELLER.
